PORTABLE WATER DISPENSING CONTAINER

Harry B. Corsaw, Palo Alto, Calif.

Application May 1, 1953, Serial No. 352,538

5 Claims. (Cl. 222—130)

This invention relates to new and useful improvements in a portable water dispensing container for installation in a motor vehicle or the like.

A principal object of this invention is to provide a tank of water which may be installed inside of an automobile where it is readily accessible but in an inconspicuous location. The tank may be conveniently filled at intervals as required and between fillings acts as a storage device for water. The tank has particular utility when traveling, particularly when it is inconvenient or impossible to stop at service stations. The tank is provided with a pump, preferably a plunger pump type as shown in Patent No. 2,362,080, which functions so as to squirt a stream of water on the hands of the user, or upon a piece of paper toweling. In this regard, a roll of paper toweling is preferably mounted in association with the tank, as will more fully appear hereinafter.

One advantage of the invention is the fact that the device is removable and portable. This enables the tank to be removed for filling and also for dispensing. For example, the tank may be placed on a picnic table to provide a water supply. In addition, when removed, the dispensing device may be used as an aid in cleaning the windshield of the vehicle or mirrors or in cleaning sticky, greasy or dirty parts of the car, such as the steering wheel.

Another important feature of the device is the fact that an auxiliary dispensing device such as a petcock may be installed which provides means for rapidly draining water from the tank. This feature has many useful advantages, one of the most important of which is to provide a means for extinguishing fires which may occur in or about the automobile.

One of the novel advantages of the invention is the fact that the cylindrical water tank may be formed with an inter-communicating hollow, smaller diameter cylinder or horn which projects out through one end of the tank, the diameter of the horn being of proper size to receive a roll of paper toweling. The paper toweling provides a means for drying the hands and face after washing. One of the features of the invention is the fact that the horn which provides the mounting for the roll of toweling is actually an extension of the water tank itself.

Another optional feature of the invention is that the end of the horn may be provided with a compartment serving as a storage place of cosmetics, such as soap, hair oil, tooth paste, hand lotion or for various pharmaceutical preparations such as aspirin, smelling salts, etc. The storage compartment opens at the end of the horn opposite the main tank.

Another optional feature of the invention is the fact that a larger and less accessible reservoir for water may be installed in the car and connected with the tank through a flexible tube. The plunger type pump employed not only dispenses water in the normal manner, but also pumps water from the reservoir to the main

2

tank even though the elevation of the reservoir may be lower than that of the tank.

When the tank is installed in position in its mounting bracket, the pump is in position for readily dispensing a spray of water which may be used to wash the hands, as, for example, before or after eating or applying cosmetics.

A source of water is provided, therefore, for sanitation and at the same time, in an integral structure, a support 10 for a roll of paper towelling. The towelling may be used for various purposes in or about the car and thus the combination of the tank and roll paper mutually increases the effectiveness of each. In addition, the source of water is valuable in case of fainting, accidents, emergency drinking water or to clean up after making minor car repairs such as changing a flat tire.

As will more fully appear, the instant invention provides a device of unusual utility which is useful in or about an automobile. It provides means for dispensing 20 water either in a spray or in a stream, depending upon the purposes for which the water is to be used.

Other numerous objects and advantages of the present invention will become apparent upon reading the following specification and referring to the accompanying 25 drawings in which similar characters of reference represent corresponding parts in each of the several views.

In the drawings:

Fig. 1 is a perspective of the device.

Fig. 2 is a transverse vertical section through the tank.

Fig. 3 is a longitudinal section taken substantially 30 along the line 3—3 of Fig. 2.

Fig. 4 is a transverse vertical section taken substantially along the line 4—4 of Fig. 3.

The present invention is designed for removable attachment in the interior of an automobile, preferably 35 under the dashboard. In order to support the device in position, a shield 11 which is generally arcuate or semi-cylindrical in section, is provided with brackets 12 suitable for attachment to a part of the car by conventional 40 fastening means. One end of shield 11 is provided with two slots 13, these slots being dimensioned to receive cooperating attachment means carried by the tank of the device. One form of attachment means is a pair of projecting ears 14 soldered or otherwise suitably fastened to 45 the tank 16 which ears project toward shield 11 and have down-turned ends 17 which fit through slots 13. Since the radius of curvature of the shield 11 and the radius of the tank 16 are substantially equal, the fastening means hook through the slots in the end of the shield and suspend the tank on the end of the shield. In this 50 manner the tank is supported with its axis horizontal but can be readily removed when desired.

It will be understood that the detachable feature of the tank is optional and that, if desired, the shield 11 and tank 16 may be formed in permanent attachment as by 55 means of soldering or welding, etc.

The tank 16 which contains the water is generally 60 cylindrical and is formed with a smaller diameter tubular roll-receiving extension or horn 21 which projects out from one end of tank 16. The extension 21 is preferably a small cylinder of sheet metal which fits inside of tank 16 through a hole in one end of the tank and is soldered to the end of the cylinder through which it projects in a water-tight joint. Horn 21, inside the tank, 65 is perforated as indicated by reference numerals 22 so that the interior of the small cylinder 21 and the interior of the large cylinder 16 are in communication, and the one constitutes an extension of the other. The external diameter of the small cylinder 21 is such as to receive a hollow roll of paper toweling 23 which is fitted over the horn extension and inside the semi-cylindrical shield 11. Thus, the shield 11 fits around the roll of paper 23 and 70

protects the same against dust, displacement, or other damage. At the same time the small cylinder 21 and the large cylinder 16 form an integral unit in that they inter-communicate and when water is filled inside the cylindrical tank it also flows inside the hollow horned extension.

If desired, the hollow horn 21 may be divided into two compartments. The inner compartment is in communication with the main cylindrical tank 16 and is normally filled with water and the outer compartment 26 is provided with a screw cap 27 at one end and having a length such as conveniently to receive articles 28 to be stored, such as, for example, toothpaste, cosmetics, soap and the like. The storage compartment 26 constitutes an extension of the horn 21 and is likewise a part of the means for supporting the roll 23 which slips over the horn. It will be apparent from the foregoing description that the cylindrical tank 16 and the horn 21 extension constitute one continuous integrated member, and that this situation obtains, whether or not the end of the horn is closed off for a storage compartment 26 or the entire horn is an extension of tank 16.

In order to fill the tank 16, a spout 31 is provided, such spout extending outwardly at an angle of approximately 45° with respect to the horizontal. The spout 31 is externally formed for threaded engagement with a cap 32. Preferably, cap 32 is fitted with a pump dispenser 33 of the general type as disclosed in Patent 2,362,080 to Martin. The outlet of dispenser 33 is directed downwardly, and thus, when the plunger 34 is depressed, in accordance with the well known operating principles of such types of pumps, water squirts through the aperture on each downward stroke of plunger. Preferably the pump 33 extends only half the depth of tank 16 so that the bottom remains filled as an available reservoir from which water may be drained through a petcock. More specifically on the bottom of cylindrical tank 16 a petcock 36 is installed, the valve of which when turned in the proper direction drains the water out of the tank.

Inasmuch as the capacity of the cylindrical tank 16 and horn extension 21 is limited, it may be desired to add extra water capacity to the device by means of an auxiliary reservoir 41 located remote from the main cylindrical tank 16. Such an auxiliary tank or reservoir 41 is connected to the principal tank by the flexible hose 42 which extends between reservoir outlet 43 and tank inlet 44, hose 42 being removable from inlet 44 when it is desired to displace the tank from its support. When the plunger 34 is depressed, water is dispensed from the pump, and on the upstroke of the pump a vacuum is created which draws water from the reservoir 41 to the main tank 16, even though the level of the reservoir may be below the main tank. Stated otherwise, as water is pumped and displaced from cylindrical tank 16, a partial vacuum is created within said tank which causes water from auxiliary reservoir 41 to flow therefrom into tank 16 in replacement of the amount of water pumped from said tank. Even when the water level in tank 16 falls below the intake end of pump 33, water from auxiliary reservoir 41 may be drawn into tank 16 upon reciprocation of pump plunger 34 which functions in such instance as a vacuum pump.

Operation

In operation, the reservoir 41, if used, is filled and the cap 32 of the main tank 16 is removed and water filled through spout 31. The cap 32 and plunger pump 33 are replaced, it being understood that the pump extends through the holes 22 in the interior part of the horn 21 and that the water in tank 16 flows into the horn 21 as well. A roll of paper 23 is placed over the external part of the horn. If a cosmetic compartment 26 is provided at the end of the horn, it is filled with the desired cosmetics 28 and screw cap 27 replaced.

Thereupon the tank 16 is hooked onto the shield 11

which has already been installed on the underside of the dash of the car, projection 14 hooking through slots 13 in shield. When thus installed, the device is out of the way and inconspicuous, yet readily accessible to the occupants of the vehicle.

The reservoir 41 provides a means for filling the tank 16 because as the plunger 34 rises, after having been depressed, it draws water from the reservoir into the principal tank.

If one of the occupants wishes to wash his hands, plunger 34 is depressed, which squirts a stream of water downwardly through the end of the plunger. Soap and cosmetics may be employed by removal from the storage compartment 26 and after washing, the paper towel 23 may be used for drying the hands. Where a considerable amount of water is required, as in filling a drinking glass, the petcock 36 is opened and sufficient amount of water drained out of the tank for the purposes intended.

When it is necessary to remove the device, the tank is unhooked from shield 11, rubber tubing 42 being disconnected from inlet 44.

Although the present invention has been described by way of illustration and example for purposes of clarity of understanding it is understood that certain changes and modifications may be made within the spirit of the invention and scope of the amended claims.

I claim:

1. In a portable water dispensing device, a shield, means for attaching said shield to a stationary support, a tank, means for supporting said tank from said shield, a hollow member projecting from one end of said tank and under said shield, said member being in fluid communication with the interior of said tank and dimensioned to receive a roll of paper towelling, and means for dispensing water from said tank.

2. In a portable water dispensing device, a shield, means for attaching said shield to a stationary support, a tank, means for supporting said tank from said shield, a hollow member projecting from one end of said tank and under said shield, said member being in fluid communication with the interior of said tank and dimensioned to receive a roll of paper towelling, a pump dispenser in said tank arranged to dispense water upon manual actuation of said pump, and means additional to said pump dispenser for dispensing water from said tank.

3. In a portable water dispensing device, a shield, means for attaching said shield to a stationary support, a tank, means for supporting said tank from said shield, a hollow member projecting from one end of said tank and under said shield, said member being in fluid communication with the interior of said tank and dimensioned to receive a roll of paper towelling, a pump dispenser in said tank arranged to dispense water upon manual actuation of said pump, and means additional to said pump dispenser for dispensing water from said tank, a reservoir for additional water, and means connecting said reservoir and tank, said pump being arranged to draw water from said reservoir into said tank.

4. In a portable water dispensing device, a shield, means for attaching said shield to a stationary support, a tank, means for supporting said tank from said shield, a hollow member projecting from one end of said tank and under said shield, said member being in fluid communication with the interior of said tank and dimensioned to receive a roll of paper towelling, a plunger type pump dispenser in said tank arranged to dispense water upon manual actuation of said pump, and means for dispensing water from said tank, and valve means for draining water from the bottom of said tank.

5. In a portable water dispensing device, an arcuate shield, means for attaching said shield to a stationary support, a tank, means for supporting said tank from said shield, a hollow horn projecting from one end of said tank and under said shield, said horn being in fluid com-

munication with the interior of said tank and dimensioned to receive a roll of paper towelling, and means for dispensing water from said tank, and a closed compartment formed at the outer end of said horn for storage of small objects.
